(57) **CLAIM**

The ornamental design for an oval air cleaner filter top, as shown and described.

DESCRIPTION

FIG. 1 is a perspective view showing the front, left side and top of the oval air cleaner filter top showing my new design.

FIG. 2 is a top view thereof;

FIG. 3 is a side view thereof;

FIG. 4 is an end view thereof; and,

FIG. 5 is a bottom view thereof.

The broken lines depict portions of the oval air cleaner filter top that form no part of the claimed design.
